KEY RING ASSEMBLY FOR KEY CHAINS

Fred W. Dittman, Rochester, N. Y., assignor to
Hickok Manufacturing Company, Inc., Rochester,
N. Y., a corporation of New York

Application May 9, 1934, Serial No. 724,808

10 Claims. (Cl. 59—98)

The invention relates to a key ring assembly for key chains.

The object of the present invention is to provide for key chains a highly ornamental key ring assembly presenting the appearance of a looped bull whip with a lash closely coiled around the handle portion of the whip and forming a continuation of the loop so that the bull whip key ring assembly will have the appearance of a complete bull whip with the entire lash portion arranged exteriorly of the handle portion without any break or interruption in the configuration of the bull whip.

A further object of the invention is to provide a key ring assembly of this character having a loop of the bull whip forming a key receiving ring and composed of two sides, one of the sides being movable with respect to the other and having a terminal engaging portion forming a portion of a spiral convolution and exteriorly embracing the other side of the loop and adapted to be readily sprung into and out of engagement with the same to open the loop to permit keys to be placed on and removed therefrom.

Another object of the invention is to provide a bull whip key ring assembly having a fixed closely coiled lash portion extending around the handle portion of the whip and having one terminal arranged at a greater pitch than the closely coiled portion and terminating at the end of the engaging portion of the movable side of the loop when the loop is closed so as to apparently merge into the said engaging portion of the loop.

With these and other objects in view, the invention consists in the construction and novel combination and arrangement of parts herein-after described, illustrated in the accompanying drawing, and set forth in the claims hereto appended, it being understood that various changes in the form, proportion and minor details of construction, within the scope of the claims, may be resorted to without departing from the spirit or sacrificing any of the advantages of the invention.

In the drawing:—

Fig. 1 is a side elevation of the key chain provided with a bull whip key ring assembly constructed in accordance with this invention.

Fig. 2 is a side elevation of the key ring assembly showing the other side thereof.

Fig. 3 is an edge view of the key ring assembly with the loop closed.

Fig. 4 is a side elevation of the key ring assembly with the loop open.

In the accompanying drawing in which is illustrated the preferred embodiment of the inven-

tion, 1 designates a key chain provided at one end with a bull whip key ring assembly and having a ring 2 at its other end for attachment to a belt, garment or the like. The ring 2 is provided with a slidably telescoping spring pressed section 3 adapted to be opened in the ordinary manner to permit the ring 2 to be engaged with and removed from a belt, garment or the like, but any other suitable form of attaching means may, of course, be employed.

The bull whip key ring assembly consists of a tapering bar 4 provided at one end with an eye or opening 5 into which is linked a ring 6 for connecting the inner end of the bar to the key chain. The bar 4 which represents a handle portion of the bull whip and a portion of the lash thereof is provided at its outer portion with a loop 7 composed of two sides and a curved connecting portion, the side 8 of the loop 7 being movable with respect to the other side which is formed by the bar 4.

The loop which is tapering forms a key receiving ring or loop and the movable side 8 is arranged at an angle to the bar 4 and is provided with a terminal engaging portion 9 consisting of a portion of a spiral convolution and adapted to exteriorly engage and embrace the bar 4 to close the loop and it is firmly maintained in engagement with the bar 4 by the resiliency of the metal of which the bull whip key ring assembly is constructed. The key chain and the key ring assembly may be constructed of precious or semi-precious metal or any other suitable material, and when the loop is opened the resiliency of the metal carries the spirally engaging portion 9 from one face of the bar 4 to the opposite face thereof and the engaging portion is adapted to form a guide for enabling keys to be readily placed on the key receiving loop of the key ring assembly.

The bar 4 and the loop thereof have a gradual taper to simulate the taper of the bull whip and the handle portion of the bar 4 is provided with a fixed member 10 closely spirally coiled around the handle portion and arranged exteriorly thereof and terminating at the engaging portion 9 of the movable side 8 when the loop is closed and the fixed spiral member 10 is provided adjacent the key receiving loop with a terminal portion 11 of greater pitch than the closely spirally coiled portion and coinciding in pitch with the engaging portion 9 of the movable side 8 of the loop so that when the latter is closed the engaging portion 9 will be in substantially abutting relation with the terminal por-

tion 11 of the fixed member and present the appearance of a continuous lash. By compressing the sides of the loop the engaging portion 9 of the movable side may be readily sprung into 5 and out of engagement with the bar 4 and when in engagement with the bar it is firmly held in contact therewith to close the loop securely.

What is claimed is:

1. A key ring assembly for key chains comprising a tapering bar having its smaller tapered portion formed into a loop composed of two sides and a curved outer connecting portion, one of the sides being resilient and movable with respect to the bar and a portion of the bar forming 15 the other side of the loop and being less resilient than the said resilient and movable side of the loop, the movable and resilient side of the loop having a hooked terminal portion to detachably embrace the bar intermediate the 20 ends of the latter when the loop is closed and adapted to be sprung out of engagement with the bar to open the loop, said terminal of the resilient movable side of the loop serving as a guide to enable keys to be readily placed on the key receiving loop when the loop is open.
2. A key ring assembly for key chains comprising a gradually tapering bar whose end of larger diameter constitutes a handle portion and whose end of smaller diameter constitutes a key 30 receiving loop possessing greater resiliency than said handle portion, said key receiving loop being composed of two sides and a curved outer connecting portion, one of the sides being movable with respect to the bar and a portion of the latter forming the other side of the loop, said movable side of the loop being arranged at an angle to the bar and being more resilient than the handle end of the bar and having a terminal hook to detachably clasp the bar at a portion 35 of the latter which furnishes support for said terminal engaging portion against bending thereof and consequent accidental detachment therefrom when the loop is closed, said terminal engaging portion being adapted to be sprung out 40 of engagement with the bar to open the loop.
3. A key ring assembly for key chains comprising a gradually tapering bar whose end of larger diameter constitutes a handle portion and whose end of smaller diameter constitutes a key receiving loop possessing greater resiliency than said handle portion, said key receiving loop being composed of two sides and a curved outer connecting portion, one of the sides being movable with respect to the bar and a portion of the latter forming the other side of the loop, said movable side of the loop being arranged at an angle to the bar and being more resilient than the handle end of the bar and having a terminal clasping hook to detachably clasp the 50 bar at a portion of the latter which furnishes support for said terminal engaging portion against bending thereof and consequent accidental detachment therefrom when the loop is closed, said terminal portion being removable 55 from engagement with the bar to open the loop and when in open position forming a guide for the passage of a key between the sides of the loop.
4. A looped retaining device comprising a 60 gradually tapering bar having its larger end constituting a handle portion and its smaller end directed outwardly and thence inwardly toward the body of the bar to form a loop, said outwardly and inwardly directed portion having a laterally directed hook constructed to detach-

ably embrace the body of the bar between the ends of the latter to close the loop and which when detached from the bar provides a guide for the ready insertion of a key between the outwardly and inwardly directed portion and the body of the bar into the loop.

5. A looped retaining device comprising a tapering bar having an end thereof directed outwardly and thence inwardly toward the bar intermediate the ends of the latter to form with the bar a resilient loop at one end of the device and to provide a handle portion at the other end of the device, the outwardly and inwardly directed portion of said loop having a hook-shaped terminal for detachably clasping relation with the bar and when detached from the bar cooperating with the latter to form a guide adjacent the inner end of the handle portion of the device for the introduction of articles into the loop and permit the removal of articles from the loop and when clasped with the bar preventing accidental displacement of the articles from the loop.

6. A looped retaining device comprising a resilient tapering bar having an end thereof directed outwardly and thence inwardly toward the bar intermediate the ends of the latter to form with the bar a resilient loop at one end of the device and to provide a straight handle portion at the other end of the device of less resiliency than the resiliency of the looped portion thereof and being roughened and at its outer end provided with an eye, the outwardly and inwardly directed portion of said loop having a hook-shaped terminal engaging portion for detachable clasping relation with the bar at the inner end of said handle portion and when detached from the bar being directed outwardly from the latter to provide a guide between the hook-shaped terminal and the bar for the insertion of articles into the loop.

7. A looped retaining device comprising a tapering resilient bar having greater resiliency at the smaller end thereof than at the larger end of the bar, said bar having the smaller end portion thereof directed outwardly and inwardly toward the body of the bar to cooperate with a portion of the bar to provide a resilient clasped loop, said outwardly and inwardly directed portion of the loop having a terminal hook for detachable clasping connection with the bar at the will of the operator and which, owing to the greater resiliency of the outwardly and inwardly directed portion of the loop and the hook thereof clasping the bar at a point of lesser resiliency to effect a firm detachable clasping of the loop in closed condition against accidental unclasping relation with said bar incident to strains due to weight of articles carried by the loop and yet under compression action upon the sides of the loop adapted to be sprung from clasping relation with the bar.

8. A key ring assembly for key chains comprising a tapering bar whose end of larger diameter constitutes a handle portion and whose end of smaller diameter constitutes a key receiving loop possessing greater resiliency than said handle portion, said key receiving loop being composed of two sides and a curved outer connecting portion, a portion of the bar constituting one of the sides of said loop and the other side of the loop being more resilient than said portion of the bar and being movable with respect to the bar portion of the loop, said movable resilient side of the loop being arranged at an angle to the bar and having a terminal engaging portion consisting of a part

of a spiral convolution and embracing the bar at the inner end of said handle portion when the loop is closed and adapted to be sprung out of engagement with the bar to open the loop and 5 when the loop is open, said terminal being maintained relatively close to the bar and directed laterally outwardly and upwardly with respect to the handle portion of the device to provide for ready insertion of keys or the like into the loop 10 or permit ready removal of the same from the loop, said terminal engaging portion spiralling outwardly with relation to the handle portion of the bar when the loop is closed.

9. A looped retaining device comprising a bar 15 having an end thereof directed outwardly and thence inwardly toward the bar intermediate the ends of the latter and having a hook to detachably embrace the bar to close the loop to form with the bar an openable loop at one end of the 20 device and to provide a straight handle portion at the other end of the device, and a coiled member encircling the handle portion of the device to roughen the handle portion and having the innermost convolution thereof terminating in an 25 abutment, said hook at its free end extending into abutting relation with said abutment when the hook is in embracing clasping relation with the bar.

10. A looped retaining device for keys or the

like comprising a tapering bar having the smaller end thereof directed outwardly and thence inwardly toward the bar intermediate the ends of the latter to form a straight handle portion at one end of the device and to form a resilient loop at the other end of the device, the loop portion of the device being of less resiliency than the resiliency of the handle portion thereof, a coiled member on the handle portion having its innermost convolution of greater pitch than the remaining convolutions of said member and providing an abutment on the bar adjacent the inner end of said loop, the inner end of the smaller portion of the bar at the looped end of the device being formed into a curved hook for detachable 15 clasping connection with the bar substantially intermediate the ends of the latter, said curved hook at its outer extremity being of cross-sectional diameter substantially the same as the cross-sectional diameter of said innermost different pitch convolution of said coiled member and abutting the inner end of said innermost coil of said coiled member when the hook clasps said bar to thereby permit said coiled member to assume a continuation of the smaller end of the bar extended as if wrapped around the handle portion 20 of the device.
